FIG. 1.

FIG. 2.

FIG. 1 is a front perspective view of a sling handle for a golf bag showing my new design.

FIG. 2 is a top plan view of FIG. 1.

The characteristic feature of my design resides in the combination of two short straps which extend upwardly from each side of the base of a golf bag and converge toward a common point from which emanates both an inner looped hand strap that is attached at the base of an upper cuff and an outer shoulder strap that is attached at the top of an upper cuff.

I claim:

The ornamental design for a sling handle for golf bag, as shown and described.
